(57) **CLAIM**

The ornamental design for a spike ring dog toy, as shown and described.

DESCRIPTION

FIG. 1 is a top perspective view of a first embodiment of a spike ring dog toy in accordance with the present invention. FIG. 2 is a top plan view of the spike ring dog toy of FIG. 1.

FIG. 3 is a bottom plan view of the spike ring dog toy of FIG. 1.

FIG. 4 is a right side view of the spike ring dog toy of FIG. 1.

FIG. 5 is a front view of the spike ring dog toy of FIG. 1. FIG. 6 is a rear view of the spike ring dog toy of FIG. 1. FIG. 7 is a top perspective view of a second embodiment of the spike ring dog toy.

FIG. 8 is a top plan view of the spike ring dog toy of FIG. 7.

FIG. 9 is a bottom plan view of the spike ring dog toy of FIG. 7.

FIG. 10 is a right side view of the spike ring dog toy of FIG. 7.

FIG. 11 is a front view of the spike ring dog toy of FIG. 7; and,

FIG. 12 is a rear view of the spike ring dog toy of FIG. 7.
